GENERATION OF PERSISTENT DISABLING GASES

Filed July 13, 1931

Inventor:
Byron C. Goss,

by Joseph W. Harris
Atty.

UNITED STATES PATENT OFFICE

BYRON C. GOSS, OF CLEVELAND, OHIO

GENERATION OF PERSISTENT DISABLING GASES

Application filed July 13, 1931. Serial No. 550,599.

This invention relates to disabling and irritating gases and gas mixtures, and to gas generating chemicals of the type which produce, or which may be readily converted into, 5 disabling and irritating gases which will persist for a relatively long period of time, and which when inhaled cause intense burning and extremely oppressive pains across the chest, and violent headache in the front 10 part of the head; the inhaled gases also cause violent nausea and vomiting and temporarily completely incapacitates a person; but the disabling effects of such inhaled gas pass off after a time so that an individual inhaling 15 the same is not permanently injured thereby.

It has frequently happened that bandits and others have broken into bank safes, vaults, post offices, jewelry stores, etc., which have been provided with gas protection systems, and have succeeded in committing unlawful acts because the particular gas used did not sufficiently punish the bandits or others, or because the effects of the gas did not persist for a sufficiently long period of time, 20 or because the bandits wore gas masks, or because the bandits left when the gas was evolved, and returned later. After having left the scene of the unlawful act, it is frequently difficult to apprehend the persons 25 committing the same, whereas if he had been made so very sick that it would not be possible for him to leave the premises for a considerable time, his capture at the scene of the unlawful act would have been more probable. 30 An object of the invention is to provide a chemical charge which will produce a disabling gas that will so completely incapacitate a lawbreaker that he will be unable to leave the scene of his unlawful acts for some 35 time.

A further object of the invention is to provide a chemical charge which will produce a disabling gas that will so completely incapacitate a person that the police authorities 40 will be aided in the capture of criminals at the scene of an attempted crime by rendering said criminals physically incapable of resisting arrest.

A further object of the invention is to provide a chemical charge which will produce a

disabling gaseous mixture which is intolerable in exceedingly low concentrations, so that the gas which is rapidly dispersed through the atmosphere by the heat and pressure generated by the force of the explosion 55 which discharges and volatilizes the mass of chemicals liberating the gas will rapidly be effective in all parts of the room in which the gas was dispersed, or when discharged in the open air will be rapidly dispersed and render a considerable area intolerable and thereby disperse or disable a large mob of 60 people.

A further object is to provide a chemical charge which will produce a disabling gas mixture which will liberate a disabling gas or gases, and which will persist in its disabling properties for a long period of time, and thereby prevent the commission of an unlawful act for a considerable period after 70 the gas has been liberated.

A further object is to provide a chemical charge which will produce a disabling gas which so completely incapacitates the person inhaling the same that he will become very 75 sick and suffer considerable pain, so much so that the person will be compelled to lie down, and will be unable to complete his unlawful acts, and will be unable to leave the premises for some time, thereby increasing the probability of his capture at the scene of his unlawful acts.

A further object of the invention is to provide cartridges, hand grenades, and similar devices with the herein described gas generating chemicals which may be discharged automatically or by hand, so that such cartridges, etc., may be used in existing installations of gas projection.

In the accompanying drawing, 90 Figs. 1, 2, and 3 are longitudinal section views of cartridges containing different types of charges of gas generating chemicals; and

Fig. 4 is a view, partly in section, of a hand grenade containing a charge of the gas generating chemicals described herein.

In Fig. 1, a cartridge shell 1 is provided with a primer 2, a charge of propellant powder, for example smokeless powder 3, a wad 4, a layer of gas generating chemical, for 100

example, diphenylamine-chlorarsine 5, a wad 6, a gelatine or other suitable capsule which may also contain some diphenylamine-chlorarsine dissolved in ethyl mercaptan, or mixture of solvents, 7, a wad 8, a seal 9, and a suitable cushion lining 10.

In Fig. 2, the propellant smokeless powder is mixed with the gas generating chemical, for example, diphenylamine-chlorarsine 12, a wad 13, a cushion 14, and a capsule 15 containing some diphenylamine-chlorarsine dissolved in ethyl mercaptan or other solvent, such as furfural, or crotonaldehyde.

In Fig. 3, the propellant, smokeless powder 17, is separated by a wad 18 and cushion 19, from the capsule 20 containing a solution of a gas generating chemical, for example, diphenylamine-chlorarsine in ethyl mercaptan, furfural, crotonaldehyde, etc., or a mixture 20 of any of these solvents.

In Fig. 4, a grenade body 25 is provided with holes or vents 26, sealed with a soft fusible metal seal 27, and then filled with a charge consisting of diphenylamine-chlorarsine, and smokeless powder 28, covered with a starting composition 29, which may consist of smokeless powder and celluloid, and the fuse head 30 attached, the fuse head is provided with a match-head 31 which is in close proximity to the starting composition. When the grenade is used, the pin 32 is withdrawn and the grenade immediately thrown, whereupon it "goes off" the seal 27 bursts, and the generated gas liberated and dispersed by the heat and pressure of the explosion.

The gas generating chemical used in this invention is preferably diphenylamine-chlorarsine, but I may also use diphenyl-amine-cyanarsine, or diphenylchlorarsine, or mixtures thereof, dissolved to about concentration in a suitable solvent, or they may be suspended in a saturated solution thereof, for example, in ethyl-mercaptan, furfural, or crotonaldehyde, or a mixture of any of these solvents.

The solution is suitably enclosed in a capsule which is placed in cartridges, etc., which latter are provided with propellant and heat generating explosives, and when fired, volatilize and rapidly disperse the generated gases over a large area, and render the atmosphere intolerable for a long time even at such low concentrations of the dispersed gas or gases as about 0.0223 mg. per liter of air for one minute exposure, or 0.0003 milligrams per liter of air for ten minutes of exposure, the concentration varying with the volume of the space into which the gases had been dispersed. The disabling effects of the gas is much more prolonged than with gases in general use, and may last for several hours, and even for a full day without producing permanent injury. A person exposed to such a low concentration of the dispersed gas generated by the chemicals de-

scribed herein would be severely punished, the inhaled gas causing nausea and vomiting, accompanied with an intense burning sensation and extremely oppressive pain across the chest, and also in most cases a violent headache in the front part of the head. The result of such exposure would be that the person would be unable to leave the place of the unlawful act but would become so violently sick that he would be compelled to lie down and be entirely incapable of resisting capture for some time. Ordinary gas masks in general use do not entirely protect the wearer against gases containing diphenylamine-chlorarsine, or the other gas generating chemicals above named.

The chemicals may be used in the following general proportions, diphenylamine-chlorarsine, or diphenylaminecyanarsine, or diphenylchlorarsine, 20 percent to about 35 percent; the balance to consist of a solvent, which may be a single or mixed solvent, for example, ethyl mercaptan, or furfural, or crotonaldehyde, or a mixture of any of these.

In Fig. 1, about 25 percent by weight of diphenylamine-chlorarsine, or diphenylaminecyanarsine, or diphenylchlorarsine, or a mixture thereof, is used, and about 75 percent of smokeless powder, as illustrated; the solution in the capsule 7 may contain from 10 percent to 25 percent of diphenylamine-chlorarsine, or other chemical indicated in ethyl mercaptan, or furfural, or crotonaldehyde, as described herein.

In Fig. 2, about 25 percent by weight of diphenylamine-chlorarsine, or other chemical indicated, is mixed with about 75 percent of smokeless powder; the solution in the capsule may be the same as in Fig. 1.

In Fig. 3, the charge of smokeless powder 17 need not necessarily contain any of the gas generating chemical but it may do so; the capsule 20 preferably contains about 25 percent of diphenylamine-chlorarsine, or other chemical indicated and about 75 percent of solvent, which may be any of those described herein, for example, ethyl mercaptan, furfural, or crotonaldehyde, or mixture thereof.

In Fig. 4, the charge in the grenade contains from about 20 percent to about 35 percent of diphenylamine-chlorarsine or other chemical indicated above, and the balance of smokeless powder; the charge is covered with a starting composition 29 as described above, and "fired" with the match-head 31.

In addition to the disabling properties which the solvents referred to herein possess, said solvents when vaporized function as vehicles for the vaporized diphenylamine-chlorarsine or other lachrymatory chemicals associated therewith.

In the claims, where diphenylamine-chlorarsine is mentioned the claims should be understood as including either diphenylamine-chlorarsine, diphenylaminecyanarsine,

or diphenylchlorarsine, or any mixture thereof, as the gas generating agent.

I claim:—

1. A unitary association containing gas generating chemicals capable of developing persistent disabling gases, consisting of diphenylamine-chlorarsine in proximity to an explosive, and a capsule containing dissolved diphenylamine-chlorarsine, said gas generating chemical adapted to be volatilized and dispersed by said explosive whereby the vaporized solvent functions as a vehicle for the vaporized diphenylamine-chlorarsine.
2. A unitary association containing gas generating chemicals capable of developing persistent disabling gases, consisting of diphenylamine-chlorarsine associated with a liquid containing diphenylamine-chlorarsine, and an explosive, whereby the vaporized liquid functions as a vehicle for the vaporized diphenylamine-chlorarsine.
3. A unitary association containing gas generating chemicals capable of developing persistent disabling gases, consisting of from 20 percent to 35 percent of diphenylamine-chlorarsine associated with a liquid containing diphenylamine-chlorarsine and an explosive, whereby the vaporized liquid functions as a vehicle for the vaporized diphenylamine-chlorarsine.
4. A unitary association containing gas generating chemicals consisting of a solution of diphenylamine-chlorarsine in ethyl mercaptan, and associated with heat generating means to volatilize and disperse said gas generating chemicals.
5. A unitary association containing gas generating chemicals consisting of a solution of diphenylamine-chlorarsine in furfural, and associated with heat generating means to volatilize and disperse said gas generating chemicals.
6. A unitary association containing gas generating chemicals consisting of a solution of diphenylamine-chlorarsine in crotonaldehyde, and associated with heat generating means to volatilize and disperse said gas generating chemicals.
7. A unitary association containing gas generating chemicals consisting of a solution of diphenylamine-chlorarsine dissolved in a mixture containing at least two of the solvents ethyl mercaptan, furfural, and crotonaldehyde, and associated with heat generating means to volatilize and disperse said gas generating chemicals.

In testimony whereof I hereby affix my signature.

BYRON C. GOSS.
